RECORDING CLOCKS
 Spurgeon Sutherland, 2113 Marilyn Lane,
 Arlington, Tex. 76010
 Filed Oct. 23, 1965, Ser. No. 503,462
 9 Claims. (Cl. 200—38)

This invention relates to new and useful improvements in recording clocks.

There are presently in existence time clock units in the use of which employees are not required to go to the time clock itself, but, instead, may punch themselves in and out at remote stations. Each employee is provided with an individually coded key or similar device, and punching in and punching out stations are located at a number of localities throughout a plant or factory, the number of stations varying, of course, with the size of the plant. Each station is provided with a punch-in keyhole and a punch-out keyhole, and to punch in an employee merely inserts his individual key in the punch-in hole and to punch out, the key is inserted in the punch-out keyhole. The unit functions to send a coded signal to a central time-keeping assembly which notes the identity of the employee from the coded signal and places this information on a punch tape, magnetic tape or the like. It is also necessary that the system record on the tape by punching or otherwise the day and time the employee punches in and the day and time the employee punches out. The present invention is directed to a clock which furnishes such time information as an electrically coded signal which can be recorded on the tape, the signal being delivered each time an employee punches in or punches out.

It is, therefore, the principal object of this invention to provide an improved recording clock which functions in a unique manner to deliver electrically coded day and time information suitable for utilization to record upon tape the working times of any number of employees.

A further object of the invention is to provide an improved recording clock having unique means for opening and closing a plurality of switches to provide a coded electric signal.

Another object of the invention is to provide an improved recording clock which is very simple and durable in structure with a minimum of shafts and other parts, in which the day, hour and minute are indicated by coded drums, there also being a drum for indicating time in seconds, all of the drums being of the same diameter and being rotatably mounted on a single fixed shaft.

Other and more particular objects will be apparent from a reading of the following description.

A construction designed to carry out the invention will be hereinafter described, together with other features of the invention.

The invention will be more readily understood from a reading of the following specification and by reference to the accompanying drawings, wherein an example of the invention is shown, and wherein:

FIG. 1 is a rear elevational view of a recording clock made in accordance with this invention, the coding dimples of the drums being omitted,

FIG. 2 is a top plan view of the clock,

FIG. 3 is a front elevational view of the clock, partly broken away to show one of the driving pinions and the coding dimples being omitted from the drums,

FIGS. 4, 5 and 6 are vertical, cross-sectional views taken upon the respective lines of FIG. 1, the driving gears for the drums being indicated by broken lines,

FIG. 7 is a view of the coded surface of the day drum unrolled into a single plane,

FIG. 8 is a view similar to FIG. 7 showing the coded surface of the hour drum,

2

FIG. 9 is a view similar to FIG. 7 showing the total surface of the minute drum,

FIG. 10 is a similar view to FIG. 7, showing the coded surface of the second drum,

FIG. 11 is a fragmentary, vertical, enlarged, cross-sectional view taken upon the line 11—11 of FIG. 2 and showing the switch actuating means, and

FIG. 12 is a view similar to FIG. 11, taken upon the line 12—12 of FIG. 2 and showing the detent structure.

In the drawings, the numeral 10 designates a top plate which has its upper surface covered by a layer 11 of dielectric or electrically non-conductive material. A vertical, rectangular end bearing plate 12 depends from one end of the top plate 10, being secured thereto by suitable bolts or screws 13, and adjacent the opposite end of the top plate, a vertical, rectangular motor mounting plate 14 also depends from the top plate in parallel relationship to the bearing plate 12 and being suitably secured to the top plate by screws or bolts 15. A fixed horizontal drum shaft 16 has its ends secured in the plates 12 and 14 and is spaced downwardly from the top plate 10 in parallel relationship therewith and toward the forward edge of the top plate. A second horizontal shaft 17 is spaced rearwardly of and parallel to the shaft 16 beneath the top plate and also has its ends fixed in the end plates 12 and 14.

A driving motor 18 is mounted upon the outer face of the plate 14 together with the usual condenser 19 normally associated with such motors. The motor 18 is desirably of a low voltage type, but may be any suitable type of small electric motor designed for constant operation and the delivery of a relatively low torque. Through a speed reducing gear box 20, the motor drives a small pinion or gear wheel 21 at a speed of one revolution per minute, the pinion 21 being disposed on the inner side of the plate 14 and meshing with a similar pinion or gear wheel 22 mounted on the shaft 16.

The pinion 22 is secured to and drives a second drum 23 rotatably mounted on the shaft 16 and carrying a circumferential annulus of indicia 24, extending, as shown in FIG. 10, from 0 to 59 for indicating the passage of time in seconds. The second drum 23 also carries on its periphery and spaced laterally of the indicia 24 a short groove or indentation 25 which may be of such length as to extend over approximately the length of five seconds as measured against the indicia 24 and the circumference of the drum 23.

On its face opposite the pinion 22, the second drum 23 carries a cam member 26 extending diametrically of the drum 23 and having a ratchet engaging finger 27 projecting radially outwardly but spaced slightly inwardly from the outer periphery of the drum 23. A ratchet wheel 28 is rotatably mounted on the shaft 17 and is of such diameter as to be engaged by the finger 27, and as will be seen more fully hereinafter, the ratchet wheel 28 is revolved and advanced the width of one tooth each time the drum 23 makes one complete revolution.

A gear wheel 29 is carried by the ratchet wheel 28 and revolves therewith, the gear wheel 29 meshing with a larger gear wheel 30 rotatably mounted on the shaft 16 and secured to one face of a minute drum 31. The minute drum 31 also carries an annulus of time indicating indicia 32 for indicating minutes, this annulus being disposed adjacent one end of the drum 31 and, as shown in FIG. 9, extending from 0 to 59 corresponding to each of the minutes in an hour.

Each complete revolution of the second wheel 23 corresponds to the passage of one minute, and the relative diameters of the ratchet wheel 28, the gear wheel 29 and the gear wheel 30 are such that each full revolution of the second wheel 23 results in the advancement of the

minute drum 31 one space or to the next succeeding minute as shown by the indicia 32.

The minute drum 31 carries on its face opposite the gear wheel 30 a cam member 33, similar to the cam member 26, and having on its end a ratchet engaging finger 34. The finger 34 is adapted to engage and revolve a ratchet wheel 35 rotatably mounted on the shaft 17 and carrying a gear wheel 36 which meshes with a gear wheel 37 rotatably mounted upon the shaft 16 and secured to one end face of an hour indicating drum 38 also rotatable upon the shaft 16.

The hour drum 38 is provided with an annulus of hour indicating indicia 39 extending circumferentially of the drum adjacent one end face thereof and running from 0 to 23, as shown in FIG. 8. Here again, the relative diameters of the ratchet wheel 35 and the gears 36 and 37 are such that for each complete revolution of the minute drum 31, the hour drum 38 is advanced one space between successive hours as indicated on the annulus 39.

On its end face opposite the gear wheel 37, the hour drum 38 carries a cam member 40 similar to the cam members 26 and 33 which functions to revolve a ratchet wheel 40 rotatably mounted upon the shaft 17 and carrying a gear wheel 42. The gear wheel 42 meshes with a gear wheel 43 rotatably mounted on the shaft 16 and secured to one end face of a day drum 44 also rotatably mounted on the shaft 16. The day drum 44 is provided with an annulus 45 extending circumferentially thereabout adjacent one end face of the drum and displaying indications of the days of the week. In order that all of the drums may be of the same diameter, for reasons explained hereinafter, the indicia 45 covers the days of four successive weeks, as shown in FIG. 7. Here again, the proportions of the driving means for the day drum is such that it is advanced one day for each complete revolution of the hour drum 38.

Summing up the operation of the structure thus far described, the motor 18 drives the second drum 23 to cause it to make one revolution per minute, the second drum drives the minute drum 31 to advance it one minute for each full revolution of the second drum, and the minute drum 31 drives the hour drum 38 to advance it one hour for each complete revolution of the minute drum. Further, the hour drum 38 drives the day drum 44 to advance it one day for each complete revolution of the hour drum. In order that the day and the date may be visually observed, there is mounted across the front of the clock between the end plates 12 and 14 a bar 46 of a transparent material such as a transparent synthetic resin, the rearward face of the bar 46 being coated with an opaque material in which there are provided apertures 47 through which the indicia of the several drums may be observed, as shown in FIG. 3.

On the upper surface of the top plate 10, overlying the insulating layer 11, there is provided printed circuitry including power leads 48 for the motor 18, a power lead 49 leading to a bus bar or strip 50 extending parallel to but slightly forward of the shaft 16. An elongate retaining strap 51, formed of an electrically non-conductive material, overlies the bus bar 50 and clamps the same to the upper surface of the top plate 10.

As previously noted, the second drum 23 revolves constantly and at a uniform speed whereas the minute drum, the hour drum 38 and the day drum 44 revolve intermittently in stepwise fashion as the minutes, hours and days elapse. In order to make certain that the latter three drums are advanced in a uniform fashion and in equal increments, as well as to ensure that they remain in their advanced positions until the next advance occurs, each is provided in its peripheral surface with an annulus of dimples or depressions cooperating with detents to accomplish the foregoing purposes. Thus, the minute drum 31 carries a peripheral annulus of dimples or depressions 52, one being alined with each of the minute indicia 32, and the top plate 10 has a vertical opening 53 overlying the

annulus of dimples 52 and positioned at top dead center over the minute drum 31. A spring metal tab or detent member 54 projects from the bus bar 50 forwardly over the opening 53 and has a centrally depressed portion 55 extending downwardly into the opening. A ball 56, formed of electrically non-conductive material, is confined between the portion 55 and the periphery of the minute drum 31 so that when one of the dimples 52 comes into alinement with the opening 53, the ball 56 will be forced downwardly by the spring tab 54 into the dimple, thus holding the minute drum against inadvertent rotation and making certain that the remaining coding dimples of the drum will be properly alined for sending the coded time signal. Similarly, the hour drum carries on its periphery an annulus of dimples or recesses 57 alined with the hour indicating indicia 39 and coacting with a spring detent finger 58 on the bus bar for similar operation. The day drum 44 has a peripheral annulus of depressions or dimples 59 alined with the indicated days of the week and functioning in conjunction with a detent finger 60 extending from the bus bar to position the day drum accurately. Of course, as subsequent rotation of the several drums takes place, the spring detent fingers will yield sufficiently to permit the advancement of the drums through one space.

The minute drum also carries additional annuli of dimples or depressions 61, 62, 63 and 64 spaced axially on the periphery of the drum and arranged in ten coded groups corresponding individually to the ten six-minute periods of an hour. This arrangement is utilized because the device in which this clock is used is primarily a payroll machine, and payrolls are conventionally calculated on the basis of tenths of a work hour.

The hour drum, in addition to the annulus of dimples 57, carries seven additional annuli of dimples or depressions, 65, 66, 67, 68, 69, 70 and 71. Various ones of the latter depressions are arranged into 24 coded patterns, each corresponding to one hour of the day and night and each being different and distinctive from the other 23 patterns.

The day drum 44, in addition to its annulus of dimples 59, carries three axially spaced annuli of additional dimples or depressions, 72, 73 and 74, positioned in four identical groups of seven different and distinct coding patterns corresponding to the seven days of the week. As previously noted, the day drum 44 undergoes a complete revolution only once every four weeks.

It is noted that all of the dimples or depressions are alined axially in their coding groups and are also alined with the indicia 32, 39 and 45, respectively.

The top plate 10 is provided with a plurality of vertical openings 75, each alined with one of the annuli of coding dimples on the time drums and one being provided for each of said annuli. An electrically non-conductive ball 76 is positioned in each of the openings 75 which are located at the top dead centers of the several drums, the balls being confined between the periphery of the drums and the armature arms 77 of leaf-type spring switches projecting from the bus bar 50 over each of the openings 75. A printed circuit conductor 78 extends from a point spaced from the opening 75 but underlying the armatures 77 over the insulating layer 11 to a multiple-pronged connector jack 79. The power supply conductors 48 and 49 are also connected into this jack.

It will be seen that as the time drums advance, selected ones of the coding dimples on the periphery thereof will come into registry with the openings 75, permitting the balls 76 to move into the dimples and the armatures 77 to move downwardly into engagement with the conductors 78 to close a circuit. In this manner, dependent upon which circuits are closed, signals are provided to the time-keeping device indicating the day, hour and minute, or rather, a particular group of six minutes. The time-keeping device receives this signal only when an employee is punching in or punching out, and his identity, together

with the time and whether he is punching in or punching out, is automatically recorded on the tape of the time-keeping device.

It is also desirable that there be furnished to the time-keeping device a signal every six minutes to indicate the passage of successive tenths of an hour, and for this purpose, the minute drum 31 has yet another annulus of dimples or depressions 80 spaced uniformly about its periphery at six minute intervals. The top plate 10 carries a spring switch 81 identical in structure to those previously described alined with the annulus of depressions 80, and an identical spring switch 82 alined with the path of travel of the groove 25 of the second drum 23. These two switches are connected through a short bus bar 83 also clamped to the upper surface of the top plate 10 by the strap 51 but electrically isolated from the bus bar 50.

Each time the second drum 23 makes a complete revolution, the groove 25 will cause the closing of the switch 82 for approximately five seconds, but no circuit will be closed because the switch 81 will be open. The switch 81 is closed once every six minutes, and when the switch 82 closes for five seconds at this time, a circuit will be completed to provide a signal to the time-keeping machine that a six-minute period has elapsed.

It is pointed out that all of the drums are of equal diameter and are rotatably positioned in axial alinement on the single fixed shaft 16. The gear wheel and ratchet assemblies are also axially alined and are rotatably mounted upon the single fixed shaft 17. Thus, the structure of the clock is maintained very simple, durable and free from likelihood of malfunction. Having all of the drums of equal diameter facilitates the visual observance of the day and time through the apertures 47 and also greatly simplifies the gearing and shafting, which would become exceedingly complex if drums of different diameters were employed.

The functioning of the recording clock is believed clear and obvious from the foregoing description, the remote stations indicating to the time-keeping device which individual employee is punching in or punching out and the recording clock furnishing at the same time coded signals indicating the day, hour and minute, the code differing for each day, each hour, and each group of six minutes in accordance with the positioning of the coding dimples and the corresponding coding difference in which of the switches of each drum are closed or opened.

The second drum 23 cannot be manually revolved due to its direct connection with the gear train 20, but the other three drums may readily be revolved manually in either direction to set the proper day, hour and minute, such rotation being limited only by the point at which its ratchet wheel comes into engagement with the finger of its corresponding cam.

The coded time signals furnished by the recording clock to the time-keeping device may be utilized in various fashions in addition to that described hereinbefore. As a different mode of operation, and under some conditions or circumstances, a preferable mode of operation, is for the recording clock to furnish a time signal to the time-keeping device only once every six minutes instead of each time an employee punches in or punches out. The punching in or punching out of the individual employees is recorded as previously described, but these indications will merely come between successive ones of the time signals which are recorded every six minutes, thus simplifying to some extent the subsequent decoding of the recording tape for payroll purposes.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A recording clock including a driving motor, a second indicating drum constantly driven by the motor, a minute indicating drum, means for driving the minute drum intermittently by the second drum, an hour indicating drum, means for driving the hour drum intermittently by the minute drum, a day indicating drum, means for driving the day drum intermittently by the hour drum, the several drums having a second, minute, hour and day indicating indicia thereon, the day drum, hour drum and minute drum having annuli of spaced depressions extending circumferentially around their outer surfaces, spring switches overlying the annuli, and balls confined between the spring switches and the outer surfaces of the drums, the balls being adapted to move into the depressions to permit the switches to close.
2. A recording clock as set forth in claim 1 wherein the balls are electrically non-conductive.
3. A recording clock as set forth in claim 1 and a detent overlying one annulus of depressions of each the day drum, the hour drum and the minute drum to hold the drums against movement between their intermittent driven movements.
4. A recording clock as set forth in claim 1 wherein the depressions of the day drum, the hour drum and the minute drum are arranged in coded groups to close selected ones of the switches and thereby provide coded signals indicating the day, hour and minute.
5. A recording clock as set forth in claim 1 wherein the second drum has a groove in its outer periphery, a spring switch overlying the annular path traced by the groove as the second drum revolves, and a ball confined between the spring switch and the periphery of the second drum adapted to move into the groove to close said switch for a predetermined period of time on each revolution of the second drum.
6. A recording clock as set forth in claim 1 wherein one annulus of depressions of the minute drum is arranged to close one of the switches every six minutes.
7. A recording clock as set forth in claim 1 wherein the second drum has a groove in its outer periphery, a spring switch overlying the annular path traced by the groove as the second drum revolves, and a ball confined between the spring switch and the periphery of the second drum adapted to move into the groove to close said switch for a predetermined period of time on each revolution of the second drum, one annulus of depressions of the minute drum being arranged to close one of the switches every six minutes, the said switch of the second drum being in series with that switch of the minute drum which closes every six minutes.
8. A recording clock as set forth in claim 1 wherein all the drums are of equal diameter and are rotatably mounted in axial alinement on a single fixed shaft.
9. A recording clock as set forth in claim 1 wherein the means for driving the minute drum, the hour drum and the day drum all include ratchet wheels and gear wheels, the ratchet wheels and gear wheels being rotatably mounted in axial alinement on a single fixed shaft.
